C. R. BROWN

METHOD AND APPARATUS FOR HANDLING WELL CASINGS

Filed May 7, 1923

Inventor
Charles R. Brown
by *W. W. Hawley*
Attorney

UNITED STATES PATENT OFFICE.

CHARLES R. BROWN, OF BREA, CALIFORNIA.

METHOD AND APPARATUS FOR HANDLING WELL CASINGS.

Application filed May 7, 1923. Serial No. 637,191.

To all whom it may concern:

Be it known that I, CHARLES R. BROWN, a citizen of the United States, a resident of Brea, county of Orange, and State of California, have invented new and useful Improvements in Methods and Apparatus for Handling Well Casings, of which the following is a specification.

This invention relates to a method and apparatus for handling well casings or the like, and it is an object of the invention to provide a simple, effective and improved method of this general character.

In drilling wells the casings are usually handled by slips and elevators, the slips being wedge devices that engage the casings at points spaced below the couplings so that the couplings can be engaged by the elevators, and the elevators being devices that engage around the casings under the couplings and between the couplings and slips to lift or move the casings by engaging under the coupling. The elevators operate reliably and effectively and are reasonably convenient to handle, but the slips are not so reliable, are injurious to casings and are inconvenient to handle.

It is an object of this invention to provide a simple, effective method of handling a casing without frictionally engaging but clamping it with slips, or the like, and without straining or injuring either the casing or the couplings.

Another object of my invention is to provide a simple, effective and convenient apparatus for carrying out the process.

Another object of the invention is to provide a form or type of elevator suitable as a part of the apparatus that may be used in carrying out the process.

The objects and features of this invention will be best and more fully understood from the following detailed description of a typical preferred form and carrying out thereof, throughout which description reference is had to the accompanying drawings, in which:

Fig. 1 is a view showing the table of a typical rotary well drilling apparatus, the table having a casing arranged through it

and supported in the manner provided by this invention, the elevator provided by the invention being shown in closed position immediately over the casing;

Fig. 2 is an enlarged side elevation of the elevator provided by the invention;

Fig. 3 is an enlarged detail sectional view of the elevator;

Fig. 4 is a plan view of the elevator, being a view taken as indicated by the line 4—4 on Fig. 3; and

Fig. 5 is a plan section, taken as indicated by the line 5—5 on Fig. 3.

In the drawings, numeral 10 designates the table of a typical rotary drilling apparatus, and numeral 11 designates a typical well casing, shown in Fig. 1, arranged through the table 10 in the usual manner. On the upper end of the casing 10 there is a coupling 12 of the type ordinarily employed to join sections of casings. I have illustrated in the drawings a rotary drilling apparatus, and will hereinafter refer to a table, or the table, of a rotary drilling apparatus merely to facilitate a clear and accurate understanding of my present invention, it being understood, however, that the invention may be carried out in situations where other types of well drilling apparatus are used, and that it is in no way limited or restricted in its scope or range of application to any form or type of drilling apparatus.

In accordance with the method provided by my invention, for handling the casing 11, the casing is handled wholly through the coupling 12 or other projecting part that may occur on the casing, and be the equivalent of the coupling 12. The method provides for supporting or holding the casing in the table by engaging under the coupling at spaced points, preferably at points substantially diametrically opposite each other, and it provides for moving the casing by engaging the coupling 12, and more particularly by engaging under the coupling 12, at the points between the points by which it is held.

In accordance with the present method, a casing 12 being held by engaging under the

coupling 12 at the upper end of the casing may be moved or lifted by engaging under said coupling at the points between the points from which it is held, and when the casing 5 has been lifted until a coupling below its upper end is above the table the casing may be again supported or held by engaging under the last mentioned coupling. It will thus be seen that a casing, or, more properly, 10 a string of casing, can be handled in the desired manner by the present method without the employment of slips or other means to engage the casing at points spaced below the couplings, in order to allow for operation 15 of the elevator.

The apparatus provided for carrying out the method includes, generally, a supporting device 14 and an elevator 15. The supporting device 14 takes the place of slips and 20 has prop parts 16 adapted to engage under the coupling 12 at spaced points to support the casing in the manner clearly illustrated in Fig. 1. The device 14 is preferably so designed that the props are movable into and 25 out of position where they will engage under the coupling 12 to support the casing so that they can be actuated to allow free movement of the casing in either direction when so desired, or to engage under the coupling to 30 hold the casing when so desired.

In Fig. 1 of the drawings I have illustrated, generally, a supporting device typical of that which may be used in carrying out my invention, and in it the props 12 are 35 pivotally carried by a frame 17 and are adapted to be actuated by means of a handle 18. This particular form or type of supporting device is more fully described and is made the subject of my copending application entitled Support for well casing, filed 40 on even date herewith, Serial No. 637,190.

The elevator 15, in accordance with my present invention, is provided with supporting parts 20 adapted to engage under the 45 coupling at the spaced points and between the points where the coupling is engaged by the supporting device. In the particular elevator illustrated in the drawings, the supporting parts 20 are relatively movable so 50 that they can be released from the position where they will engage under the coupling to allow for the elevator being arranged on and removed from the casing and coupling. In this particular application I make reference in detail to this particular type of elevator, and I have claimed this particular type of elevator, but I do not thereby mean that the broader aspects of my invention 55 should be understood as limited to this or any other specific construction of elevator.

In accordance with the preferred form of my invention the supporting parts 20 of the elevator 15 are provided with upwardly facing shoulders 30 adapted to support the coupling. The supporting parts 20 are not di-

rectly connected but are connected through flange parts 31 which extend outwardly and around from the sides of the supporting parts and are pivotally connected together at one side of the elevator by pivot pin 32 and 70 are releasably connected together at the other side of the elevator by a suitable latch device 33. When the elevator is in place around a coupling and casing the inner walls 34 of the supporting parts more or 75 less closely engage the casing at substantially diametrically opposite points, while there is a substantial space 35 between the flange parts 31 and the casing to allow for the reception of the prop parts 16 of the supporting device. When the elevator is arranged around a casing and coupling and the latch 33, which, by the way, may be of any suitable type or form and need not be of the T-type which I have illustrated in the drawings, is closed the structure which I have just described completely encircles the casing, is strong and rigid and has spaced parts, the shoulder 30, adapted to engage under the coupling to carry the casing in a 80 particularly secure and reliable manner. The flanges and supporting parts are preferably cast or otherwise formed integrally, as I have shown in the drawings, so that the structure is particularly rigid and solid. 85

Above the supporting parts 20 and flanges 31 I provide guide parts 35 which come together as I have illustrated in Fig. 4 to completely encircle the coupling when the device is applied to the casing and coupling. The 90 guide parts are proportioned so that they more or less closely fit on the coupling and thereby operate to steady or brace the elevator in position and make it impossible for the elevator to shift or move in a manner to allow the coupling to become displaced from the shoulders 30. The guide parts 35 are 95 preferably formed integral with the other parts above described, as I have illustrated throughout the drawings. The elevator is provided with suitable suspension means 40 which, in the particular case illustrated in the drawings, comprises bails 41 carried by 100 suitable ears 42 extending from the two sections of the elevator. 105

From the foregoing description of the method provided by this invention, and from the detailed description of the construction of the elevator it will be obvious 110 how the elevator can be conveniently and effectively used to carry casings in substantially the same manner that ordinary elevators do. To apply the elevator the two sections are brought together so that the shoulders 30 are below the coupling to engage 115 under the coupling and are made secure by the latch device 33. If the elevator is applied to a coupling engaged by the supporting device 14 the elevator is applied so that the supporting parts 20 come between the 120

props 16. It will be obvious, of course, that the various parts, for instance, the props, the supporting parts 20 and the flange parts 31, may be designed and proportioned so 5 that the supporting parts 20 will be guided into position between the props 16 upon the elevator being closed so that the elevator can be handled in the same manner as any other elevator. Before releasing the elevator 10 from the casing and coupling the casing is lowered or positioned so that the props 16 of the supporting device are engaged under a coupling. The coupling engaged by the 15 props does not, of course, have to be the coupling engaged by the elevator although it may be, as will be apparent from the foregoing description.

Having described only a typical preferred form of my invention I do not wish 20 to limit myself to the specific details hereinabove set forth but wish to reserve to myself any changes or variations that may appear to those skilled in the art or fall within the scope of the following claims.

25 Having described my invention, I claim:

1. The hereindescribed method of handling a casing with a coupling on it including, holding the casing by engaging under the coupling at spaced points, and moving 30 the casing by engaging under the coupling at points between those first mentioned.

2. The hereindescribed method of handling a casing with a coupling on it including, holding the casing by engaging the coupling, and moving the casing by engaging 35 the same coupling.

3. The hereindescribed method of handling a casing with a coupling on it including, holding and moving the casing wholly through the coupling substantially as described.

4. The hereindescribed method of handling a casing with a coupling on it including, holding the casing by engaging under 45 the coupling at substantially diametrically opposite points, and moving the casing by engaging under the coupling at points between those first mentioned.

5. Apparatus for handling a casing with 50 a coupling on it including, a prop adapted to engage under the coupling to hold it, and a movable support adapted to engage under the coupling to move it.

6. Apparatus for handling a casing with 55 a coupling on it including, a prop adapted to be carried by a stationary support to engage under the coupling, and an elevating support adapted to engage under the coupling.

60 7. Apparatus for handling a casing with a coupling on it including, two relatively movable parts adapted to handle the casing by engaging under the coupling, one part being a relatively stationary prop and 65 the other being a movable elevating part.

8. An elevator for a casing having a coupling on it including, two spaced parts adapted to engage under the coupling.

9. An elevator for a casing having a coupling on it including, two spaced supporting parts each having a shoulder adapted to engage under the coupling.

10. An elevator for a casing having a coupling on it including, two supporting parts having shoulders to engage under the 75 coupling at spaced points.

11. An elevator for a casing having a coupling on it including, supporting parts adapted to be assembled around the casing and having parts to engage under the 80 coupling at spaced points.

12. An elevator for a casing having a coupling on it including, two pivotally connected parts adapted to be arranged around the casing, the parts having spaced shou 85 ders to engage under the coupling.

13. An elevator for a casing having a coupling on it including, two spaced supporting parts adapted to engage under the 90 coupling, and flange parts connecting the supporting parts and being spaced from the casing.

14. An elevator for a casing having a coupling on it including, two spaced supporting parts adapted to engage under the 95 coupling, flange parts extending outwardly and around from the supporting parts, the flange parts at one side of the elevator being pivotally connected together, and means for releasably connecting the flange parts at 100 the other side of the elevator.

15. An elevator for a casing having a coupling on it including, two spaced supporting parts adapted to engage under the 105 coupling, and means for guiding the supporting parts in position with relation to the coupling.

16. An elevator for a casing having a coupling on it including, two relatively movable spaced supporting parts adapted to be arranged to engage under the coupling, and means for bracing the supporting parts in position with relation to the coupling.

17. An elevator for a casing having a coupling on it including, two spaced supporting parts adapted to engage under the 115 coupling, and guide parts above the supporting parts to engage the coupling.

18. An elevator for a casing having a coupling on it including, two relatively movable spaced supporting parts adapted to be arranged to engage under the coupling, and guide parts adapted to embrace the coupling when the supporting parts are in position to engage under the coupling.

19. An elevator for a casing having a coupling on it including, two spaced supporting parts adapted to engage under the coupling, flange parts extending outwardly and around from the supporting parts, the 130

flange parts at one side of the elevator being pivotally connected together, means for releasably connecting the flange parts at the other side of the elevator, and guide parts
5 adapted to engage around the coupling when the supporting parts are in position under the coupling.

In witness that I claim the foregoing I have hereunto subscribed my name this 18th day of April, 1923.

CHAS. R. BROWN.
